MACHINE FOR BREAKING AND DECORTICATING BAST FIBERS

David E. De Lape, Pasadena, Calif.

Application March 17, 1937, Serial No. 131,383

8 Claims. (Cl. 19—22)

My invention relates to a machine for breaking and decorticating bast fibers, and while it is of general application, it is especially intended for use in the treatment of ramie or China grass.

It is an object of this invention to provide a machine simple of construction and efficient in operation whereby the fibers of ramie and similar material may be decorticated in a minimum of time and without injury to the fiber.

In particular, my invention contemplates the construction of a stationary floor, preferably inclined in the direction of the travel of the material treated, said floor being provided with a series of spaced parallel teeth arranged transversely to the line of travel of the material. A stationary guide frame is arranged above the floor in which a plurality of beaters are slidably mounted. Each beater is provided with independent springs tending to move the same toward the floor. On each side of the guide frame a beater operating bar is disposed which engages fingers laterally extending from the beaters, said operating bars being lifted to engage the fingers and raise the beaters and then by a quick return movement permitting the beaters to strike with considerable force the material passing along the floor.

With the above and other objects in view, which will appear as the description proceeds, my invention consists in the construction, arrangement, and combination of parts hereinafter described and claimed.

In the accompanying drawings, which form a part of this specification, I have illustrated a preferred embodiment of my invention, and in which:

Figure 1 is a side elevation showing two of the machines arranged in series with a waste material separator interposed between the two machines.

Fig. 2 is a side elevation of the machine with parts broken away for clearness of illustration.

Fig. 3 is a vertical, longitudinal section.

Fig. 4 is a section on the line 4—4 of Fig. 3.

Fig. 5 is a section on the line 5—5 of Fig. 3.

The two machines illustrated in Figure 1 arranged on different levels are connected in series with a separator interposed between. These two machines are exactly alike in construction and the description of one will apply to both.

The machine is mounted on a base foundation of concrete or the like 10. On account of the violent vibrations it is essential that a firm foundation be provided. The frame of the machine 11 is securely anchored thereto by angle irons 11

and comprises a pair of parallel side walls 12 between which a strong floor 13 is built. The floor 13 consists of a series of wooden planks 14 arranged on edge and held together by rods 15 which have their ends secured in the side walls 12. 5

As shown in the drawings, the foundation 10 and the machine mounted thereon is inclined downwardly and rearwardly. The top of the floor 13 is faced with a metal sheet 21 and shaped to provide a plurality of teeth 16, each tooth comprising an upper face 17 disposed horizontally and which starts from the bottom of the short vertical face 18 of the tooth preceding except the first tooth at the intake chute 20. The teeth are arranged transversely to the line of travel of the 15 material to be treated. The lower end of the floor 13 connects with a delivery chute 22 for conveying the treated fiber from the machine.

A stationary guide frame 23, preferably made of wood, is secured to the floor 13 and comprises 20 a pair of vertical side members 25 to which pairs of metal bars 24 are secured with their upper ends projecting upwardly therefrom. The upper ends of each pair of bars 24 are slotted at 24' to which a U-shaped metal frame 34 is secured by means 25 of bolt 35. Fast to and disposed between the side members 25 a series of guide boards 26 is arranged, the boards being equally spaced from each other providing vertical slots therebetween in which beaters 28 are slidably mounted. The 30 beaters are preferably made of wood with the grain disposed vertically and at right angles to the bottom edge 28'. In order to prevent splitting transversely to the grain of the wood, each beater 28 is provided with a transverse metal rod 35 29 the ends of which are countersunk therein, one end being provided with a head 29' and a nut 29" at the other. At the top of each beater there is a wooden bar 30 joined thereto by a dovetailed construction 31, the grain of the wooden 40 bar 30 being in the direction of the length of the bar. Each beater 28 is provided with a pair of laterally extending fingers 31' preferably made of metal rods having their inner ends screwed into the sides of the beater 28, said fingers at 31' 45 being arranged at opposite sides of the beater and at some distance from the lower edge thereof and projecting through slots 25' in side members 25.

Secured to and extending upwardly from each 50 beater 28 and fastened to the wooden bar 30 is a pair of guide rods 32. The upper ends of the guide rods 32 pass through perforated bars 33 extending parallel to the side members 25 of the guide frame 23. The bars 33 engage transversely 55

disposed cushioning beams 40 which secure the underface of the horizontal portion of the U-shaped metal frame 34. Each rod 32 is encircled by a helical spring 36 interposed between the 5 perforated bar 33 and the wooden bar 30 of the beaters 28, the springs 36 tending to move the beaters 28 downwardly toward the floor 13. The beaters 28 are arranged in sets of three, each set 10 engaging one tooth 17 of the floor. It should be noted that the last beater of each set has its lower end pointed as at 37, to provide a sharp edge while the other two beaters have their lower ends square. On account of the angular 15 inclination of the beaters 28 the square faces of the beaters will strike the horizontal face of tooth 17 at a slight angle while the pointed end 37 will pass closely adjacent the vertical edge 18 of the tooth. In this manner, each beater 28 will strike the material passing along the floor 13 20 with an edge instead of its entire face in its action to decorticate the bast fiber.

The mechanism for operating the beaters 28 is as follows:

A pair of operating bars 38 one on each side of 25 the guide frame 23 is provided and the forward and rear ends are united by transverse connecting rods 39 provided with antifriction rollers 41 engaging the front and rear faces, respectively, of the side members 25 of guide frame 23. These 30 operating bars 38 are given an upward and quick-return downward movement by means of a pair of quick-return cams 42 arranged to engage the underface of the forward and rear ends of each bar 38. These cams, as seen on Fig. 2, are rotated 35 in a clockwise direction and their construction is such that as the cam rotates the convex face 42' of the cam will gradually raise or lift the bars 38 until it reaches the extreme end of the convex face 42' when the bars will be moved downwardly 40 quickly by the action of springs 36 operatively connected to the fingers 31'. The cams 42 are operated by a pulley 44 deriving its power from a source (not shown). The cams 42 at the rear end of the machine are fast to shaft 43 on which 45 pulley 44 is mounted. A sprocket wheel 46 also fast to shaft 43 is operatively connected to shaft 47 to which the forward cams 42 are mounted by means of chain 45 and sprocket wheel 50.

Operation

The material to be decorticated such as ramie, and the like, is fed down the intake chute 20 onto the floor 13. The operating bars 38 in their upward movement engage the lateral fingers 31' of the beaters 28 and lift the same against the 50 tension of the springs 36. As soon as the cams pass the extreme upper lifting movement to permit the operating bars 38 to fall freely, the beaters 28 would be forced downwardly under the 55 action of the springs 36 and strike the ramie a sharp blow with an edge of the lower face of the beaters as previously explained. It should be noted that those beaters which engage the ramie adjacent the vertical section 18 of the teeth 16 60 will not only bend and break the bast and pithy portions of the material but cause a slight forward movement. In addition thereto, a certain amount of vibration of the machine is unavoidable and due to the inclination of the floor 13 65 toward the delivery chute 22, the material will move in that direction so that no other means for conveying the material through the machine is necessary. The tension of the spring 36, and therefore the force of the blow of the beaters 28 70 may be adjusted as desired by the slotted con-

nection between the U-shaped frame member 34 and the vertical bars 24.

It is advisable to arrange the machines in sets of two connected in series as shown in Fig. 1, and to interpose a separator 48 between them so 5 that the delivery chute 22 of the first machine will convey the treated material to the separator 48. The separator ordinarily consists of longitudinal slots and a reciprocating tooth conveyor 49 conveying the fibers onto the intake chute 20 10 of the second machine but causing the waste material consisting of the woody particles, pith, and the like, to pass through the separator. By this arrangement the action of the beaters of the second machine is at its maximum efficiency not 15 being interfered with by any pithy particles except those which still adhere to the fibers.

It should also be noted that the beaters 28 are independently mounted for downward movement by the action of independent springs 36 so that 20 each beater irrespective of the amount of material that it strikes exerts its maximum force. This would not be the case if all the beaters were connected and operated as a unit.

Various changes may be made in the details of 25 construction without departing from the spirit or scope of the invention as defined by the appended claims.

I claim:

1. A machine for breaking and decorticating 30 bast fibers, comprising an inclined stationary floor provided with a plurality of teeth arranged transversely to the movement of the material to be treated, a feeding chute for delivering material to the floor and a delivery chute conveying 35 treated material from the floor, a stationary beater guide frame above the floor and provided with a series of guide slots, a series of beaters separately mounted for independent downward movement and adapted to strike the floor and 40 mounted for slidable movement in the guide slots, each beater being provided with a pair of fingers laterally projecting from opposite sides of the guide frame, separate spring means connected to each beater and mounted in the guide frame 45 and tending to move the beaters toward the floor, a pair of vertically reciprocating operating bars arranged on opposite sides of the guide frame and engaging the lower side of the fingers, cam members to move the operating bars upwardly against 50 the tension of the springs, said cams being so constructed as to permit a quick-return movement of the operating bars by the spring means to force the beaters with a striking blow against the floor.

2. A machine for breaking and decorticating 55 bast fibers, comprising an inclined stationary floor provided with a plurality of transverse teeth and having a feeding chute at one end and a delivery chute at the other, a stationary beater guide frame 60 above the floor and provided with a series of guide slots, a series of beaters separately mounted for independent downward movement and adapted to strike the floor and mounted for slidable movement in the guide slots, each beater being provided 65 with a pair of fingers laterally projecting from opposite sides of the guide frame, spring means mounted in the guide frame tending to move the beaters toward the floor, a pair of vertically reciprocating operating bars arranged on opposite sides 70 of the guide frame and engaging the fingers, and means for operating the operating bars.

3. A machine for breaking and decorticating 75 bast fibers, comprising a stationary floor provided with a plurality of transverse teeth, a sta-

tionary beater guide frame above the floor, a series of beaters separately mounted for independent downward movement and adapted to strike the floor and mounted for slidable movement in the guide frame, separate spring means for each beater tending to move the beaters toward the floor, a pair of vertically reciprocating operating bars arranged on opposite sides of the guide frame and operatively connected to the beaters to lift them upwardly against the tension of the spring means, and means for operating the operating bars.

4. A machine for breaking and decorticating bast fibers, comprising a solid stationary floor provided with a plurality of transverse teeth, a stationary beater frame above the floor, a series of beaters independently mounted for downward movement in the guide frame and adapted to strike the floor, independent spring means for each beater to move the same toward the floor and means for lifting the beaters upwardly against the tension of the spring means and permitting the beaters to move downwardly independent of each other.

5. A machine for breaking and decorticating bast fibers, comprising a solid stationary floor provided with a plurality of transverse teeth, a stationary beater guide frame above the floor, a series of beaters adapted to strike the floor and mounted in said guide frame, spring means mounted in the guide frame and tending to move the beaters toward the floor, and means for lifting the beaters upwardly against the tension of the spring means and permitting the beaters under the action of the spring to strike a quick blow against the floor.

6. A machine for breaking and decorticating bast fibers, comprising an inclined stationary floor provided with a plurality of transverse teeth, each tooth having a substantially horizontal portion and a smaller vertical portion, a beater guide frame above the floor, a series of beaters slidably mounted in the guide frame, the lower ends of the beaters being shaped to strike the floor edgewise, springs mounted in the guide frame tending to move the beaters toward the floor, a pair of vertically reciprocating operating bars arranged on opposite sides of the guide

frame operatively connected to the beaters to lift them against the tension of the springs and to permit them under the action of the springs to move downwardly to strike a blow against the floor.

7. A machine for breaking and decorticating bast fibers, comprising a stationary floor provided with a plurality of transverse teeth, a beater guide frame above the floor, a series of beaters mounted for independent downward movement and adapted to strike the floor edge-wise and mounted for slidable movement in the guide frame, spring means tending to move the beaters toward the floor and vertically reciprocating means arranged on opposite sides of the guide frame and operatively connected to opposite sides of the beaters for lifting them against the action of the spring means and permitting them to strike a downward blow against the floor.

8. A machine for breaking and decorticating bast fibers comprising in combination a solid stationary floor having a downward inclination from its upper toward its lower end, the floor being provided with a series of teeth, each tooth having an upper face disposed substantially horizontally and a vertical face, the vertical face being materially of less measurement than the horizontal upper face, the horizontal face of a lower tooth terminating at the lower end of the vertical face of the next higher tooth, a series of stationary guide boards, a beater board positioned between adjacent guide boards, the guide boards having plane surfaces and being mounted at a slight tilt to the vertical, certain of the beater boards having square ends and others having pointed ends, means for lifting the beater boards upwardly, independent springs connected between each beater board and a fixed structure and compressed on the upward movement of its beater board, the beater board being thrust downwardly by the reaction of the spring, the beater boards with square ends being adapted to engage material on the horizontal flat faces of a tooth and the beater boards with the sharp edges being adapted to engage the material adjacent the vertical face of a tooth.

D. E. DE LAPE.
